[57] **CLAIM**

The ornamental design for an artificial limb, as shown and described.

DESCRIPTION

FIG. 2 is a front elevational view of an artificial limb, showing my new design, with a waist strap;

FIG. 2 is a rear elevational view thereof;

FIG. 3 is a left side elevational view thereof, with the waist strap removed;

FIG. 4 is a bottom plan view thereof;

FIG. 5 is a top plan view thereof;

FIG. 6 is a right side elevational view thereof;
FIG. 7 is a front elevational view of a second embodiment of an artificial limb, with a waist strap;

FIG. 8 is a rear elevational view thereof;

FIG. 9 is a right side elevational view thereof, with the waist strap removed;

FIG. 10 is a bottom plan view thereof;

FIG. 11 is a top plan view thereof; and,

FIG. 12 is a left side elevational view thereof.

The broken line showing in FIGS. 1 and 7 is for illustrative purposes only and forms no part of the claimed design.
